UNITED STATES PATENT OFFICE

WILHELM SCHLEIFER, OF VIENNA, AUSTRIA

RIDER FOR REGISTRATION CARDS

Application filed May 17, 1928, Serial No. 278,604, and in Austria March 23, 1928.

This invention relates to a rider for registration cards, which is securely mounted on the latter in such a manner, that it cannot slide upwardly, downwardly or laterally.

5 One mode of carrying out the present invention is illustrated by way of example on the accompanying sheet of drawings in which:—

Fig. 1 shows a part of a registration card 10 with the rider applied thereto, and

Fig. 2 is a sectional view, the section being taken on line A—A of Fig. 1.

The rider consists of a sheet-metal strip which is bent upon itself so as to provide two 15 arms of different lengths. In the illustrated embodiment the corners of the long arm *a* are cut off, while the short arm *b* is provided with an inwardly bent projection *c*. It is of importance that the distance of this projection from the bend of the sheet-metal strip correspond to the distance of slits from 20 the edge of the card *i*, the said slits being provided in the latter and extending parallel to the said edge.

25 As shown in Fig. 2, the rider is firmly mounted on the card, because the bend of the rider finds a secure hold in the slit *d* of the card *i*, while the inward projection *c* rests on the edge of the said card.

30 As illustrated in Fig. 1, the registration cards are provided with a number of slits *d*, *e*, *f*, *g* and *h*, which are spaced from the edge of the card *i* just the same distance as the projection is from the bend of the rider. The 35 latter can be readily passed through the slit, because the corners of the long arm *a* of the rider are cut off.

The rider may be made of any desired material of sufficient elasticity and the two arms 40 may be of equal lengths.

Instead of providing the rider with a projection as shown in the drawings, the same may be furnished with punch-marks, 45 projections or the like, or a wire-clip forming the rider may be provided with bends, which enable the rider to rest on the edge of the card.

I claim:—

50 1. An index tab for a card having a slot parallel to and spaced a given distance from

an edge of the card, said tab comprising a pair of substantially parallel arms of elastic material connected together at one end and unconnected at the other end, and a projection on one arm directed toward the other 55 arm, said projection being spaced from the connected end of the arms a distance substantially equal to that which the slot in the card is spaced from the edge of the card, whereby when the tab is in position in the 60 card the projection will overlie the edge of the card.

2. An index tab for a card having a slot parallel to and spaced a given distance from 65 an edge of the card, said tab comprising a strip of flexible material bent on itself and forming arms of unequal length tending to move toward each other, and a projection on one arm directed toward the other arm, said projection being spaced from the bend a distance substantially equal to that which the slot in the card is spaced from the edge of the card, whereby when the tab is in position in the 70 card, the projection will overlie the edge of the card. 75

In testimony whereof I affix my signature.

WILHELM SCHLEIFER.
